UNITED STATES PATENT OFFICE.

JOHN W. DAVIS, OF WASHINGTON, DISTRICT OF COLUMBIA, ASSIGNOR TO UNDERWOOD TYPEWRITER COMPANY, OF NEW YORK, N. Y., A CORPORATION OF DELAWARE.

TYPEWRITING MACHINE.

Application filed August 20, 1925. Serial No. 51,320.

This invention relates to a card-holding attachment for the platen of a typewriting machine. More particularly it relates to means whereby the device may be easily attached to and removed from the machine, so as to permit the handling of other work besides the typing upon cards.

According to this invention, the card-holding device is slipped into place, and, by means of suitable clamps, the same is positively locked against the axle of the platen. The platen is then positioned so that the gripping elements on the device are substantially at the top of the platen, and the upper edge of the card is inserted therein, whereupon the platen is rotated forwardly to wind the card therearound past the feed-rolls, which co-operate with the card-holding device to hold the card in typing position.

One of the features of this invention relates to the clamping device provided at each or either end of the card-holding device to positively hold it upon the platen. The device consists of a rigid piece of sheet-metal straddling the platen and having forked ears at the ends engaging with flattened portions of the platen-axle to positively locate the card-holding device relatively to the periphery of the platen. The clamps are pivotally mounted upon studs fast to the forked ears, and, when urged by pressure exerted upon finger-pieces forming an integral part thereof, the clamps are swung to either their effective or ineffective position. In order to positively hold the clamps in their locked position, there is provided a detent-pin or projection which may be attached or struck out in the metal, thus forming an obstruction for the finger-pieces, thereby preventing the accidental release of the clamps.

Other features and advantages will hereinafter appear.

In the accompanying drawings,

Figure 1 is a front view of the platen of a typewriting machine having the card-holding device applied thereto.

Figure 2 is an end view in elevation of the platen of the typewriting machine, and shows the card wrapped therearound and held thereon by means of co-operating feed-rolls.

Figure 3 is a similar view, showing the clamping means for the card-holding device in its released position.

Figure 4 is a perspective view, showing

the card-holding device removed from the machine.

The card-holding device is illustrated in Figure 4 removed from the platen of the machine, and comprises a cross-piece 10 bent to conform with the curvature of the platen and extending the full width thereof. Said cross-piece terminates at the ends thereof with downwardly-extending ears 11 into which there are cut elongated slots 12 straddling flat portions 13 of a platen-axle 14. The device itself is in turn designed to straddle a platen 15, as shown in Figure 1, in which position it is held closely bearing upon the periphery of the platen by means of 70 clamping members 16.

The clamping members 16 are pivotally mounted at 17 on the downwardly-extending ears 11 and are normally held by friction against the ears in a position as shown in Figures 3 and 4, thus leaving a clear opening for the platen-axle. In order to lock the clamping members it is only necessary to swing them rearwardly to a position as shown in Figure 2, wherein they are held by 75 means of a round-headed or suitably shaped pin or projection 18, which may be struck out of the metal. Owing to the comparatively high ratio of leverage between the binding portion 19 of the clamping members 16 and the finger-pieces 20, which extend at the other end of the fulcrum point, it will be apparent that a slight friction of the finger-pieces against the pin 18 will be sufficient to positively hold the locking members 80 in their effective positions, and that a comparatively small pressure on the finger-pieces will be required to clear the pin when it is desired to release the clamping members 85 preparatory to removing the device from the 90 machine.

According to the method of handling the work in this device, a card 21 is inserted, leading edge first, under card-holding teeth 22 in the cross-piece 10, and is bent downwardly, as shown in Figure 1. The platen is then rotated rearwardly, or in line-space direction, so as to wrap the card around the platen, as shown in Figure 2, in which position it is held by means of co-operating feed-rolls 23, to be typed upon by means of 100 typing instrumentalities, represented by a type-bar 24.

It will be noted that in order to permit the rotation of the platen, the finger-pieces 110

of the locking members 16 are designed below the cylindrical contour of the platen, so that the latch will not strike the rear table or chute, not shown, but usually found in the

8 Underwood and other machines.

The clamping member is in the form of an elbow lever having a short arm or binding portion 19, which catches under the collar or axle 14 and thereby cramps the card-holder down upon the platen. The long arm of the lever carries the finger-piece 20, and this arm is relatively thin or weak and is sprung to the right at Figure 2 enough to enable it to reach the right-hand side of projection 18, behind which it catches, whereby the lever is in normally strained condition and therefore efficiently cramps the card-holder down on the platen. In passing the projection 18, the lever may be also sprung a trifle to one side to clear the projection. While the card-holder is shown provided at both ends with the clamping levers, still one of said levers may be omitted in some cases, as will be understood by those skilled in the art.

Variations may be resorted to within the scope of the invention, and portions of the improvements may be used without others.

Having thus described my invention, I

30 claim:

35 1. A card-holder for use on the cylindrical platen of a typewriting machine, including a metal strip extending the full width of the platen and having a row of teeth punched up at intervals, said teeth being slightly set out to receive the leading edge of a card, said metal strip terminating with downwardly-extending forked ears designed to straddle the hubs of the platen, and means

40 for locking the card-holder upon the platen, said means including locking members actuating under the platen axle to force the metal strip against the periphery of the platen, and means for operating and for resiliently locking the locking members.

45 2. A card-holder designed to hold the leading edge of a card wrapped around the platen of a typewriting machine having co-operating feed-rolls, including a metal strip terminating with forked ears straddling the platen axle, means for locking the card-holder upon the periphery of the platen, and means for locking said locking means.

50 3. A card-holder designed to hold the leading edge of a card wrapped around the platen of a typewriting machine having co-operating feed-rolls, including a metal strip terminating with forked ears straddling the

platen axle, means for locking the card-holder upon the periphery of the platen, said means including latches pivotally mounted upon the forked ears, each latch being provided with finger-pieces forming an integral part thereof, and means including interposing elements co-operating with said finger-pieces to hold the latches in their locked positions.

55 4. A card-holder designed to hold the leading edge of a card around the platen of a typewriting machine having underlying feed-rolls, means for positively securing the card-holder upon the platen, said means including two locking members rockably mounted upon ears forming an integral part of the card-holder and straddling the platen, said locking members being resiliently held in their locked positions by means of interfering elements forming an integral part of said ears.

60 5. A card-holder designed to hold the leading edge of a card around the platen of a typewriting machine having underlying feed-rolls, said card-holder including a cross-piece bearing upon the periphery of the platen and having gripping elements for receiving the leading edge of the card, and forked end pieces forming an integral part of said cross-piece, and means for positively holding said forked end pieces to the axle of the platen, said means including a latch at each end of the platen rockably mounted upon said forked pieces, means including finger-pieces for operating said latches, and means for locking said latches in their effective or closed positions.

65 6. A card-holder designed to hold the leading edge of a card around the platen of a typewriting machine having underlying feed-rolls, said card-holder including a cross-piece bearing upon the periphery of the platen and having gripping elements for receiving the leading edge of the card, and forked end pieces forming an integral part of said cross-piece, and means for positively holding said forked end pieces to the axle of the platen, said means including a latch at each end of the platen rockably mounted upon said forked pieces, means including finger-pieces for operating said latches, and means for locking said latches in their effective or closed positions, said last-mentioned means including protruding elements in said forked pieces in the path of the finger-pieces of said latches.

JOHN W. DAVIS.
